UNITED STATES PATENT OFFICE.

WALTER E. BROWN AND ALPHA L. HOLADAY, OF MUNCIE, INDIANA.

OPERATING-TABLE.

1,209,549.

Specification of Letters Patent. Patented Dec. 19, 1916.

Application filed November 29, 1915. Serial No. 63,961.

To all whom it may concern:

Be it known that we, WALTER E. BROWN and ALPHA L. HOLADAY, citizens of the United States, residing at Muncie, in the county of Delaware and State of Indiana, have invented certain new and useful Improvements in Operating-Tables, of which the following is a specification.

This invention relates to improvements 10 in apparatus for facilitating surgical operations upon animals.

The present invention is embodied in, and consists of the new construction, combination and arrangement of parts shown in the 15 annexed drawings in which the different parts of the device are identified by similar characters of reference applied thereto in the several views: in which—

Figure 1 is a front view, and Fig. 2 is a 20 plan view of our improved operating table. Fig. 3 is a transverse sectional view taken on the line 3—3 in Fig. 1, and Fig. 4 is a transverse sectional view taken on the line 4—4 in Fig. 1.

The flat table top 1 is supported on suitable standards or legs 2, 2^a, 3 and 3^a. Arranged in alinement with the leg 2^a is an upright guide bar 4. Between this guide bar and the inner face of the leg 2, and retained against displacement by side strips 5, is disposed slidingly a vertical arm 6. Carried by this arm 6 is a head block 7 which registers above a head block 8 secured to the table top. The facing surfaces of 35 these head blocks are hollowed out, in form as shown in Fig. 3. A lever designated as 9 has its rear end supported loosely on a suitable stud or bolt 10 that is secured to the leg 2^a. A connecting bar 11 has its upper end loosely connected to the member 6 and its lower end is in similar manner connected to the lever 9. Arranged on the side of the leg 2 is a toothed bar or rack 12. A tooth 9^a secured on the side of the lever 9 40 engages the teeth of the rack. By a coil spring 13 the lever 9 is urged upwardly, the upright 6 and its head block 7 being supported normally at the raised position shown in Fig. 3. A guide bar 2^b serves to 45 prevent transverse displacement of the lever 9 when same is shifted apart from its normal engagement with the rack 12.

15 designates a longitudinal slot, and 16 designates a slot in the table top, arranged 50 in direction diagonal to the table's edge.

A lever 17, similar in arrangement to the

lever 9 hereinbefore referred to, has its rear end loosely connected to the leg 3^a and is retained at the raised position by a spring 18. A tooth 17^a carried by the said lever engages the rack bar 19 that is secured to the side of the leg 3. A guide bar 3^b serves to prevent transverse displacement of the lever 17 when same is shifted apart from its normal engagement with the rack 19.

A flexible strap 20 made preferably of leather, has its one end passed underneath the roller 21 that is carried on a loosely connected arm 22 of the lever 17, and is fastened to the underside of the table-top. The upper and free end of the strap is provided with a hook 23 that is adapted to be placed in engagement with the eye-block 24. This eye block has a shank 24^a that loosely occupies the slot 16 and is arranged in loose engagement with a retaining bar 25 that is secured at position below and in alinement with the slot 16.

Rising from the table at the location shown in Fig. 2 is a support arm 26. In holes 26^a in this support arm are retained loosely the hemp cords 27 having loop ends as shown. 26^b and 26^c designate fins formed integral with the arm 26. In the V-shaped openings provided by these fins, the cords 28 when drawn therein are held tightly.

Our improved operating table is especially intended for use in the work of castrating pigs. This important operation, otherwise difficult, and attended by numerous dangers, both to the operator and to the animal, is, by our invention, rendered comparatively simple and easy of accomplishment. The operation is possible of accomplishment by a single individual, liability of 95 accident is reduced to a minimum, and facility for medical treatment and the application of antiseptics is afforded.

The manner of using the invention is as follows:—The animal is disposed on the table top its head being passed over the block 8. The operator with his foot depresses the lever 9 which lowers the head block 7 until the neck of the animal is held securely. The band 20 is then drawn about the animal's body the hook 23 being placed at engagement with the eye block 24. The operator, with his right foot then lowers the lever 17 which causes the band to tighten against and to hold the body of the animal 110 against movement. It will be understood that by the operation of the tooth of each

of the levers 9 and 17 engaging the respective rack bars 12 and 19, the said levers are retained securely at the lowered positions. By having the elongated slot 15, and the 5 range of adjustment provided for the eye block 24 by the slot 16, it is apparent that the device is capable of being handled to accommodating animals of different sizes. The animal having been secured at place, the 10 next step is to secure its feet against movement. The loops of the cords 24 are fastened to the feet and the free ends of the cord are then drawn taut over the arm 26 and brought into tightened condition at the 15 fins. With the animal thus held at position on the table top the operator is afforded every facility for performing the operation and for the administration of such treatment as may be necessary.

20. What we claim as our invention, and desire to secure by Letters Patent, is:—

1. In an operating table, the combination of means to hold the animal's head, an eye

block capable of being adjusted to different positions on the table top, a flexible band having its free end adapted to be detachably connected to the eye block, and means operable from below the table top to tighten and hold the band.

2. An operating table comprising a pair 30 of head blocks, means operable from underneath the table to move the head blocks to and to hold same at closed position, an eye block capable of being adjusted to different positions on the table top, a flexible band having its free end adapted to be detachably connected to the eye block, and means operable from below the table top to tighten and hold the band.

In testimony whereof we affix our signatures in presence of two witnesses.

WALTER E. BROWN.
ALPHA L. HOLADAY.
